CLAIM

The ornamental design for an absorbent article, as shown and described.

DESCRIPTION

FIG. 1 is an isometric view of an absorbent article, showing my design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is an enlarged front view thereof taken from FIG. 2. The dash-dash-dash broken line showing in the Figures shows portions of the absorbent article and forms no part of the claimed design. The dash-dot-dash broken lines indicate the areas from which the corresponding enlargements are taken and form no part of the claimed design.
